UNITED STATES PATENT OFFICE.

JAMES A. MONTGOMERY AND HENRY HANSEN, OF UKIAH, CALIFORNIA.

TRACTOR-WHEEL.

1,179,179.

Specification of Letters Patent. Patented Apr. 11, 1916.

Application filed September 9, 1915. Serial No. 49,709.

To all whom it may concern:

Be it known that we, JAMES A. MONTGOMERY and HENRY HANSEN, citizens of the United States, and residents of Ukiah, in the county of Mendocino and State of California, have invented a new and Improved Tractor-Wheel, of which the following is a full, clear, and exact description.

This invention relates to traction vehicles and has particular reference to tractor wheels having an endless flexible belt tread and a main load supporting wheel coöperating with said tread.

Among the objects of the invention is to simplify and generally improve this class of devices in respect to the reliability of operation and durability.

With the foregoing and other objects in view the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which

Figure 1 is a side elevation of our improved tractor wheel; Fig. 2 is a vertical transverse section on the line 2—2 of Fig. 1; and Fig. 3 is a transverse sectional detail on the line 3—3 of Fig. 1.

Referring now more particularly to the drawings, we provide an endless flexible tread member in the form of a chain belt comprising a plurality of chains 10 shown as four in number operating in parallelism and of the same length. These chains comprise links 11, pivoted to one another at 12 and arranged in pairs, the chain links of each pair of links being connected by the same pivots 12.

The traction portion of the belt comprises a series of corrugated shoes 13, each having a lip 13' overlapping the adjacent end of the next shoe. The corrugations of the shoes are substantially flat with respect to the longitudinal dimension. They are also substantially flat transversely except that they are turned inwardly slightly at the side edges, as indicated at 13". Each shoe 13 is connected to an arch member 14 comprising inner and outer V-shaped parts 14^a and 14^b. The feet portions of these arches are arranged in parallel vertical planes, the feet

14' and 14" on one side of the structure being connected to one pair of chains 10 while the corresponding feet on the other side are connected to the other pair of chains. These feet are connected to the several chains by means of strong rivets 15 or their equivalent. The two parts of the arch are connected to each other also by rivets 16 or their equivalent near the apex of the arch. The inner member 14^a is concaved or curved away from the apex of the other member leaving a longitudinal bearing socket for the bolt 17 serving to pivotally connect the adjacent shoe to such arch. The ends of the bolt or longitudinal pivot 17 are connected in inwardly projecting ears 18 of the shoe, such ears being formed as parts of the reinforcing plate 19 secured on the inner face of each shoe. This pivotal connection between the shoes and the chains provides for a certain amount of free, lateral tilting of the several shoes over rough or uneven surfaces.

The structure includes two pairs of sprocket wheels 20, each pair being connected by a transverse shaft 21. Each wheel 20 comprises a disk-like web between its hub and the rim 22. Each rim 22 consists of a smooth bearing flange for coöperation with the outer chain of each pair, and a series of sprocket teeth 23 coöperating with the pivot pins 12.

As above premised, the primary load support of the structure consists of a smooth-faced wheel 24, mounted upon an axle 25, upon which the vehicle and the motor may be supported. The inner chains of the two pairs of chains have direct bearing contact with the smooth periphery of the load support 24 and mid-way between the vertical planes of the shafts 21. The shaft 25 is journaled in bearings 26 guided for vertical reciprocation between guides or struts 27, which together with longitudinal bars 28, constitute a pair of trusses on opposite sides of the load support and driving sprocket wheels. The ends of the truss bars 28 are rigidly connected to bearing blocks 29 in which the shafts 21 are journaled. The bearings 26 are resiliently spaced from the upper and lower bars 28 by means of cushions in the form of coil springs 30, which relieve the machine or vehicle from excessive shocks due to the passage over stony or otherwise rough surfaces.

31 indicates a motor shaft journaled in the bearing 32 secured to the upper portion

of the truss. The inner end of the shaft 31 carries a driving pinion 33 having roller teeth 34 coöperating directly with the driving sprocket teeth 23. The driving pinion 33 is suitably located and of such a size as to coöperate directly with both driving sprocket wheels on the same side of the tractor, and since the sprocket wheels on the other side of the structure are rigidly connected through their shafts 21 to the sprocket wheels driven by the pinion there is a substantially rigid driving connection from the motor to all of the sprocket wheels.

18. We claim:

1. In a tractor wheel, the combination of two pairs of driving wheels each of which is provided with a periphery having toothed and smooth portions, a truss frame on each side of all of the traction wheels, front and rear shafts connecting the ends of the truss frames upon which the pairs of wheels aforesaid are journaled, a load supporting wheel having a smooth periphery and journaled in the truss frames intermediate the transverse shafts aforesaid, a traction belt including a plurality of chains coöperating with the load supporting wheel periphery and the smooth portions of the traction

wheels, said chains being arranged in pairs, 30 the links of adjacent pairs being connected by pivots coöperating with the toothed portions of the traction wheels, and means to rotate the traction wheels.

2. In a tractor wheel, the combination of 35 a plurality of chains, means to positively propel the chains in parallelism, a series of rigid arches connected to all of the chains, said arches having their apexes extending longitudinally and centrally of the tractor 40 and a series of tread shoes pivotally connected to said apexes.

3. In a tractor wheel, the combination of 45 two pairs of sprocket chains operated in parallelism, means to propel the chains, a series of arches, each arch comprising inner and outer arch members, the outer arch members being connected to the outermost chains and the inner arch member being connected to the innermost chains and a series of tread shoes connected to the apex 50 portions of the arches.

JAMES A. MONTGOMERY,
HENRY HANSEN.
